UNITED STATES PATENT OFFICE.

CARL SCHUSTER, OF BELLEVUE, PENNSYLVANIA, ASSIGNOR OF ONE-HALF TO
CHRISTIAN N. BERGMANN, OF PITTSBURGH, PENNSYLVANIA.

KNIFE-SWITCH.

1,086,622.

Specification of Letters Patent.

Patented Feb. 10, 1914.

Application filed July 6, 1909. Serial No. 506,054.

To all whom it may concern:

Be it known that I, CARL SCHUSTER, a citizen of the United States, residing at Bellevue, in the county of Allegheny and State of Pennsylvania, have invented certain new and useful Improvements in Knife-Switches, of which the following is a specification, reference being had therein to the accompanying drawing.

10 My invention consists in an improvement in knife switches and is particularly designed to provide a switch of large ampere capacity and ample contact area with the requisite strength, efficiency for the objects 15 in view and simplicity and cheapness of construction. In switches of this type it is desirable to provide good contact area and conducting cross section for the current, for which purposes I have provided a plurality 20 of contacting elements and a corresponding plurality of connecting switch blades mounted on an insulating base, in the manner hereinafter more fully described.

In the drawings accompanying the application: Figure 1 is a view of the device in side elevation. Fig. 2 is a plan view of Fig. 1. Fig. 3 is a cross sectional view on the line III. III. of Fig. 1, showing continuous contact conductors. Fig. 4 is a similar view 30 showing a modified construction and combining a plurality of blade contacts with conducting bus bar connections. Figs. 5 and 6 are similar views showing further modified constructions.

35 2 represents the base of the switch of any suitable form and construction, of insulating material, as slate, etc., adapted to be mounted on a switch board or elsewhere for operation with the elements to be connected. 40 Like all switches of this type, the base is provided generally with conducting members connected with the terminals of the circuit conductors 3 and 4, and a movable switch blade or blades pivotally connected 45 to one set of such conductors and adapted to establish make-and-break connection with the other terminal.

In my construction I provide for the desired area of contact and conducting efficiency by assembling at a suitable location on the base, a plurality of conductors 5 for the pivotal mounting of the blades 6 and a similar plurality of contacting members 7 for engagement by the blades.

50 55 The groups of conductors 5 and 7 are gen-

erally alike in construction and number and each group consists of sets of pairs of flat bars as indicated in the cross sectional view, Fig. 3, which in such form are shown continuous and are indicated by the numeral 60 7'. A number of each pair of bars 7' are rigidly held in their relative position as to each other and to the base 2 by separators 8 which need not however, be insulating separators, inasmuch as the entire series of bars 65 7' constituting the complete conductor 7 are intended to carry the whole current, the object being to provide ample area for contact of the blades 6.

The bars 7' are embraced by a rectangular 70 frame 9 mounted upon the base 2 and secured thereon by holding bolts 10, while transverse bolts or rivets 11 extending through opposite sides of the frame 9 and through all of the bars 7' fixedly secure 75 them in position. At their other ends, the bars 7' are all secured in contact with any suitable connection conductors, as bus bar or other similar connecting elements 12, with which the current conducting terminal 80 communicates, by suitable clamping devices. The upper end of the contacting bars 7 are preferably divided as indicated in Fig. 1, to insure sufficient resiliency to make proper engagement with the blades 6 and may be 85 suitably formed otherwise to insure proper insertion and contact of the blades. The corresponding group of conductors 5 is similarly mounted in the base 2 and between 90 each pair of conductors are mounted by a pivoting belt 13 the several blades 6 in the manner usual with switches of this type. The other ends of the conductors 5 are similarly connected with bus bars or other conductors 14 by which connection is made to 95 the other terminal of the circuit, as will be readily understood. The blades 6, which correspond in number to the number of pairs of the contact and conducting bars 5 and 7, are provided at their front ends with 100 a handle 15 of any suitable construction, connected with the blades by suitable attaching means whereby all of the blades are rigidly maintained in position and operable 105 by the handle as will be readily understood.

In Fig. 4 the contact and conducting bars are shown as composed of two parts consisting of the contact members 7^a extending through the frame 9' and supplemental extensions 7^b overlapping said contact mem-

bers as shown, in pairs, both of said sets of bars being secured within the frame and bases by the same means already described. The advantage of this construction is that I am thus enabled to utilize shorter lengths of bars while securing the full efficiency of their conductivity and all of the other advantages of the invention, with the double blade arrangement at each side of each bus bar element.

In Fig. 5 the contact and conducting bars 7^a and 7^c are lapped upon extension bars 7^d and framed together in the same general manner, providing more closely adjacent bus bar connections, while in Fig. 6 the same effect is produced by extending the bars 7^e clear through and bringing them together in pairs below the base 2. In all forms I provide a plurality of closely adjacent conductors of broad area and carrying capacity for connection with the blades or bus bar elements, as disclosed.

It will be observed that in each construction the conductors which provide the hinge mounting for the blades and also the contacts therefor, are practically continuous clear through from one side of the base 2 to the other, comprising conductors of undiminished area and contact surface for the bus bar connections co-extensive with the area of the blade portions. The conductors are also separated, although they constitute

practically one-piece posts or bars. This is due to the overlapping of the conductors themselves, of full length or otherwise as shown, and the intervening separators or spacers 8 extending between the face of base 2 at one side and the top of frame 9 at the other. Between these points the conductors and spacers form a laminated middle portion of the composite conducting element or bar.

What I claim is:

1. The combination with an insulating base, of a series of assembled thin flat conductor bars and spacers both extending through the base and overlapping each other within the base, and a holding frame fixedly secured to the bars and spacers and to the base.

2. An electric switch comprising a slab or panel of insulating material, a plurality of contact strips extending through the slab or panel and spacing strips interleaved with the contact strips and also extending through and outwardly from one side of the panel to constitute a terminal member of the switch.

In testimony whereof I affix my signature in presence of two witnesses.

CARL SCHUSTER.
